UNITED STATES PATENT OFFICE.

DAVID WELLER, OF NEW YORK, N. Y.

DESIGN FOR AN AUTOMOBILE FLOWER VASE.

Application filed December 31, 1925. Serial No. 15,916. Term of patent 3½ years.

To all whom it may concern:

Be it known that I, DAVID WELLER, a citizen of the United States, and a resident of the city of New York, borough of Manhattan, in the county and State of New York, have invented a new, original, and ornamental Design for an Automobile Flower Vase, of which the following is a specification, reference being had to the accompanying drawing, forming part thereof.

The figure is a perspective view of an automobile flower vase, showing my new design.

I claim:

The ornamental design for an automobile flower vase, as shown.

DAVID WELLER.
